(57) **CLAIM**

The ornamental design for a multi purpose portable cold cathode fluorescent lamp, as shown and described.

DESCRIPTION

FIG. 1 is a front view of the multi purpose portable cold cathode fluorescent lamp showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof; and,

FIG. 8 is a perspective view thereof with various parts shown in an alternate position.
